[57] **CLAIM**

The ornamental design for tibial component extender and tool for implantation, thereof.

DESCRIPTION

FIG. 1 is a perspective view of a tibial component extender and tool for implantation thereof and shows details of the receptacle for the tibial component; FIG. 2 is a rear elevational view thereof;

FIG. 3 is a cross section view of the present invention along line 3—3 of FIG. 2;

FIG. 4 is a top plan view thereof;

FIG. 5 is a front elevational view thereof;

FIG. 6 is a bottom plan view thereof; and

FIG. 7 is a right side elevational view thereof.
